UNITED STATES PATENT OFFICE.

NORMAN C. BASSETT, OF LYNN, MASSACHUSETTS, ASSIGNOR TO GENERAL ELECTRIC COMPANY, A CORPORATION OF NEW YORK.

MEANS FOR ELECTRICALLY OPERATING COUNTER-SHAFTS.

SPECIFICATION forming part of Letters Patent No. 729,716, dated June 2, 1903.

Application filed February 27, 1902. Serial No. 95,925. (No model.)

To all whom it may concern:

Be it known that I, NORMAN C. BASSETT, a citizen of the United States, residing at Lynn, county of Essex, State of Massachusetts, have 5 invented certain new and useful Improvements in Means for Electrically Operating Counter-Shafts, of which the following is a specification.

This invention relates to mechanism for 10 driving counter-shafts for machine-tools; and its object is to enable such a shaft to be actuated by an electric motor and to be rotated in either direction without reversing the motor.

15 The invention consists in an electric motor mounted on a suitable base-plate, which can be secured to a ceiling or wall, as desired, a counter-shaft journaled in a movable frame, a friction-wheel on the counter-shaft having 20 two concentric faces for engaging a friction-pinion on the motor-shaft, and a device, either mechanical or electrical, for moving the frame and causing one or the other of said faces to engage with the pinion. When the 25 face larger in diameter is in contact with the pinion, the wheel and the counter-shaft are rotated slowly in one direction. When the smaller face is in mesh, the shaft is rotated more rapidly in the reverse direction.

30 In the accompanying drawings, Figure 1 is a front elevation of my invention on the counter-shaft side. Fig. 2 is a bottom plan view of the same. Fig. 3 is an end elevation. Fig. 4 is a rear elevation. Fig. 5 is a front elevation 35 of the lower end of the cam-lever, on a larger scale. Fig. 6 is a cross-section of the same on the line 6-6, Fig. 5. Fig. 7 is an end elevation of a modification, showing an electromagnet for operating the rocking frame. Fig. 8 is a 40 longitudinal section of the electromagnet, and Fig. 9 is a diagram of circuits.

The base-plate A has lugs *a*, by means of which it can be fastened to overhead beams B or to a wall, if desired. On the base-plate 45 is secured an electric motor C. Depending from the base-plate are lugs A' to support the movable frame D, preferably a rocking frame, hinged on an axis parallel with that of the motor-shaft. The frame is provided with 50 bearings, in which is journaled a counter-shaft E, provided at one end with a stepped cone-

pulley F and at the other with a driving wheel or pulley G, having two concentric faces *g* *g'*, with an annular space between them to receive a driving-pinion C on the motor-shaft. 55 The space is wide enough to permit the pinion to rotate without touching either face of the pulley; but a slight movement of the rocking frame will shift the pulley radially and bring one face or the other into contact with 60 the pinion, the pinion being in a radius of the pulley substantially at right angles to the plane of the frame-hinges and counter-shaft.

The motor is arranged to run continuously 65 in one direction. When the face *g* of the driving-pulley is brought against the pinion, the counter-shaft will be rotated in one direction at a certain speed. When the face *g'* is moved into contact with the pinion, the pulley and counter-shaft will be rotated in the 70 reverse direction at a faster speed, the face *g'* being of less circumference than the face *g*.

To rock the frame D, I may use either mechanical means, as shown on Sheets 1 and 2 of the drawings, or an electrical device, as 75 shown on Sheet 3. The mechanical device consists, preferably, of a lever H, fulcrumed at *h* and carrying two cams I and K, engaging with the end of an arm D', projecting from the rocking frame. When the lever is 80 moved in one direction from a central position, the cam I forces down the arm D' and brings the face *g* of the pulley into contact with the pinion. On moving the lever the other way the cam K lifts the arm and 85 reverses the movement of the pulley. The cams are preferably adjustable lengthwise of the lever, as by means of the adjusting-screws L and clamping-screws M. Each cam has an inclined face *i* *k* to impart movement to the 90 arm D' and a face *i' k'*, concentric with the fulcrum of the lever, to hold the lever and arm in their operative position.

To operate the lever H, a long lever N may be provided, extending down near to the operator and connected with the lever H by a link P. By means of this lever N the operator 95 can cause the machine-tool belted to the cone-pulley to be started, stopped, and reversed at will.

Instead of the cams I may employ solenoids to actuate the arm D', as shown on Sheet 3 of

the drawings. The arm is held normally in a central position by one or more springs, the preferred construction being shown in Fig. 7, in which a rod R passes through a lug a' on the base-plate and a lug d on the arm D'. A spring R' between these lugs and another spring R² between the lug d and a washer r at the lower end of the rod keep the arm normally in a central position, with the faces $g\ g'$ out of touch with the pinion C'. The actuating-solenoids S S' are preferably two in number, having a common axis and arranged in a suitable housing T and supported from the base-plate, as by depending studs T'. The armatures U U' of the solenoids are attached to a rod V, on which they are adjustable by screw-threads and lock-nuts, and the rod is pivotally connected with the end of the arm D'. When the upper solenoid is energized, the arm D' is drawn down and the machine-tool is started. If the lower solenoid is energized, the machine is reversed.

A simple form of controller-switch is shown in Fig. 9. The main lines are numbered 1 and 2. A branch 3 runs from the positive line to a fixed finger 3'. Fingers 4' and 5' are connected, respectively, by leads 4 and 5 with the solenoids S S'. Another finger 6' connects with a lead 6 in shunt to the solenoids. The three leads 4 5 6 are connected in multiple with one terminal of the motor C, whose other terminal connects with the negative side 2 of the main circuit. A movable set of contact-

plates 3^a 4^a 5^a 6^a, all connected together, serve to connect one of the fingers 4' 5' 6' with line 35 1 at will, and thus start, reverse, or stop the counter-shaft without stopping the motor. The pull of the solenoid being in proportion to the armature-current, the pressure between the friction pinion and pulley is in the same 40 proportion.

What I claim as new, and desire to secure by Letters Patent of the United States, is—

The combination with an electric motor, of a counter-shaft, a driving-pulley on said shaft 45 provided with two concentric faces, a pinion on the motor-shaft adapted to engage with said faces, a rocking frame in which the counter-shaft is journaled, an arm on said frame, springs for holding the arm normally in a 50 central position, two solenoids having a common axis and connected in series multiple with said motor, and a rod carrying the armatures for said solenoids and connected with said arm, and means for causing the line- 55 current to pass through one or the other of the solenoids at will, whereby the direction of rotation of the counter-shaft can be reversed without reversing the motor.

In witness whereof I have hereunto set my 60 hand this 25th day of February, 1902.

NORMAN C. BASSETT.
